A. F. WESTLAND.
GASOLINE ENGINE.
FILED MAY 13, 1921.

INVENTOR
A.F. WESTLAND.
BY *O.H. Bond*
ATTORNEY.

UNITED STATES PATENT OFFICE.

ALGOT F. WESTLAND, OF BROWNLEE, SASKATCHEWAN, CANADA.

GASOLINE ENGINE.

Application filed May 18, 1921. Serial No. 462,103.

To all whom it may concern:

Be it known that I, ALGOT F. WESTLAND, a citizen of the Dominion of Canada, residing at Brownlee, in the county of Moose Jaw and Province of Saskatchewan, Canada, have invented certain new and useful Improvements in Gasoline Engines, of which the following is a specification.

The present invention relates to improvements in gasoline engines, the principal objects being to provide an engine of the character described, which will have a maximum amount of power, less piston vibration, and be simple and compact in construction.

With these and other objects in view, the invention consists in the construction, combination, and arrangement of parts, as will be hereinafter fully described, illustrated in the accompanying drawing and pointed out in the claims hereunto appended.

The drawing is a top plan view illustrating part of the cylinder heads in section.

Referring to the drawing, like numerals designate like parts in the drawing.

The numeral 1 indicates the base, having substantially mounted thereon a pair of cylinders 2 and 3. Pistons 4, 5, 6 and 7 are slidably mounted in the cylinders 2 and 3, each pair of pistons being connected by a rod 8. Each pair of pistons are substantially connected by bracket members 9, as indicated diagrammatically.

The cylinders will be preferably cast intact, having slotted openings 10 on the interior side and registering opposite each other to allow the reciprocation of the bracket members 9 therein. These bracket members 9 are secured to the reciprocating piston rod 11, slidably mounted in bearings 12 and 13. On the outer end of this piston rod 11, is connection rod 14, suitably mounted on and functioned to actuate the crank 15 configurated on the transverse crank shaft 16, which shaft is journaled in bearings 17 and 18. On the outer ends of the transverse crank shaft 16 are mounted fly wheels 19 and 20, functioned to add impetus to the rotation of the said transverse crank shaft. Bevel pinions 21 and 22, mounted on the transverse crank shaft 16, drive bevel pinions 23 and 24, mounted on the vertical shafts 25 and 26. These vertical shafts 25 and 26 are journaled in bearings 27 suitably positioned on the base 1. Bevel pinions 28 and 29 mounted on the ends of the vertical shafts 25 and 26, drive bevel pin-

ions 30 and 31, mounted on transverse shaft 32, which is journaled in bearings 33, mounted on the cylinder heads. Bevel pinions 34 and 35 drive bevel pinions 36 and 37, mounted on the transverse shafts 38 and 39, journaled in bearings suitably positioned on the base 1.

These transverse shafts 32, 38 and 39 are functioned to actuate by means of cams 40 the intake and exhaust valves 41 and 42 positioned in the ends of the cylinders. Spark plugs 43 are suitably mounted on the cylinders for ignition.

As indicated diagrammatically, the gas ⁷⁰ that would be behind piston 4 is about to be exploded. The spent gas in front of piston 5 is about to be expelled through the open exhaust valve 42. Gas from the manifold is entering intake valve 41 into the cylinder ⁷⁵ before piston 6, while the gas in front of piston 7 is about to be compressed.

The explosion of the gas before piston 4 forces the combined piston forward. The actuating of the cams opens exhaust valve 42 ⁸⁰ before piston 5, allowing the escape of the spent gas to a suitable exhaust. Simultaneously, intake valve 41 opens and the gas enters into the chamber before piston 6. The gas in the chamber before piston 7 is thus ⁸⁵ compressed.

One the return stroke the compressed gas before piston 7 is fired forcing the combined pistons back. The gas in the chamber before piston 6 is compressed. The actuating cams automatically close the exhaust and open the intake valve into the chamber before piston 5. The exhaust valve before piston 4 is opened, and the spent gas expelled. Each successive stroke causes reciprocation of the piston rod 11, which in turn, imparts rotation of the fly wheels.

From the foregoing, it is thought that the construction of my invention will be clearly understood, and, therefore, a more extended ⁹⁰ explanation has been omitted.

What I claim as new is:

1. In a gasoline engine of the character stated, a pair of cylinders cast integral with registering slots adjacent each other, pistons in pairs in each cylinder, bracket members extended through said slots and connected to said pistons, a piston rod connected with said bracket members, and a rod connected with the crank shaft for actuating the said piston rod.
2. In a gasoline engine of the character

stated, a pair of cylinders cast integral with registering slots adjacent each other, pistons in pairs in each cylinder, bracket members extended through said slots and connected to said pistons, a piston rod connected with said bracket members, and a rod connected with the crank shaft for actuating the said piston rod, said cylinders be-

ing formed with bearings through which said piston rod reciprocates.

In testimony whereof I affix my signature in the presence of two witnesses.

ALGOT F. WESTLAND.

Witnesses:

ELMER ORAMME,
EDWIN WESTLAND.
